SUPPORTING APPARATUS

William C. Eddy, Kenilworth, Ill., assignor to
Radio Corporation of America, a corporation of
Delaware

Application January 3, 1941, Serial No. 373,002

6 Claims. (Cl. 248—325)

My invention relates, in general, to movable supporting members, and more particularly to such members as are commonly called "mike" booms or microphone booms.

In sound or aural broadcasting, and for such purposes as the recording of the sound track on talking moving pictures, it often-times becomes necessary or desirable to provide a pick-up microphone arrangement which may be easily moved from point to point in order to best cover the program or material which is sought to be broadcast or recorded. Elaborate arrangements have been provided heretofore for fulfilling this purpose, and these arrangements have had undesirable features. Accordingly, it is one of the objects of my invention to provide a microphone boom or support by means of which it is possible to cover substantially all of the individual sections making up a complete predetermined area.

Again, the microphones have had to have either an operator very close to the microphone, or elaborate arrangements had to be provided for operating the microphone from a distance. Accordingly, it is another of the objects of my invention to provide a microphone boom or support which may be easily operated and operated remotely therefrom.

Among the severe disadvantages that the somewhat elaborate arrangements heretofore known have suffered is that the support for the microphone was necessarily held by a somewhat bulky movable pedestal, and in the case of transmission of such programs such as television programs, the microphone boom had to be prohibitively long, or if not, the supporting pedestal for the boom was constantly in the way of the television cameras, particularly in obtaining "close-up" views. The arrangement contemplated in this invention is such that it may be used in a television or sound broadcasting studio and may be attached to the ceiling thereof, thus preventing conflict between the other apparatus necessary to the program and the boom itself. Accordingly, it is another of the objects of my invention to provide a microphone boom or support which may be attached to the ceiling or an elevated support and may be desirably operated therefrom, although it will be appreciated that this apparatus could be worked successfully either from a mounting on the floor or the side wall.

In view of the fact that television studios at the present time must be especially adaptable to television needs, and further, since most of these studios at the present time are comparatively small, anything that contributes to independence of operation of the various units associated in a television broadcast has a distinct advantage. It has been pointed out hereinbefore that television cameras must move into various positions in order to obtain the most desirable "shots" and un-

less the microphone boom was entirely unwieldy and too long, the pedestal for the boom was constantly in conflict with the television cameras. Accordingly, it is another of the objects of my invention to provide a microphone support or boom arrangement which is particularly adaptable to the uses of television.

Again, due to the fact that the studios at the present time are somewhat small and further, since a considerable amount of material is necessary in order to light and pick up a television program and further, since a very rapid change from character to character may be necessitated, it is highly desirable that the microphone arrangement be such that not only may the device be brought near the character, but must be able to move to considerably spaced apart distances very rapidly and very accurately. The sliding type of boom which has been known heretofore cannot satisfactorily fulfill these conditions. Accordingly, it is another of the objects of my invention to provide a microphone boom or support arrangement which may be changed from character to character extremely quickly with a speed and accuracy not contemplated by, nor possible with the sliding type of microphone boom.

Again, since all of the characters in a broadcast are not of the same height, and since sound must be picked up from a character whether in a sitting or standing position, it is necessary that the microphone be adapted to be changed in vertical position rapidly and accurately. It will be seen from the hereinafter contained description how this is made feasible with the arrangement hereinafter to be described. Accordingly, it is another of the objects of my invention to provide a microphone boom or support arrangement which may be vertically adjusted rapidly and accurately.

My invention, in general, comprises providing a plurality of interrelated arm members which are pivotally engaged with each other, and these arm members are controlled remotely by means of power transmission apparatus such as cables, ropes, or the like, and these cables are arranged so that the relative movement of the cables determines the relative movement of each of the plurality of pivotally supported members with reference to the support member for the entire apparatus. Thus, by governing this angular relationship, any portion of a predetermined area may be covered by a microphone supported at or near the extremity of one of the members, the member being preferably that which is farthest from the support of the entire apparatus.

My invention will best be understood by reference to the figures in which:

Fig. 1 is a partially cut-away drawing of the entire apparatus.

Fig. 2 is a somewhat simplified showing of the entire apparatus, and

Fig. 3 is a particular showing of the remote control features of the apparatus.

Referring to Fig. 1, there is shown a partially broken away embodiment of the apparatus. The plate 10 may be fastened to the ceiling or an appropriate supporting means, and joined to 10 is an apertured support member 11 whose function will be more fully explained hereinafter. Two arm members 12 are joined to the plate 10 by bolt and nut members 13, the arm members extending downwardly and being bent under at their lower extremity 14 where they are joined to member 11. Also connected to plate 10 is a shaft 15 which is connected through an abutment or flange 16 to the member 10 by bolt and nut members 17 and 18. The opposite lower end of this shaft ends in an abutment plate 19 whose function will be explained more fully hereinafter. The shaft 15 passes through the aperture in the member 11 and is abutted on either side thereof by collars 20 and 21, respectively.

Surrounding the shaft 15 and positioned at the lower extremity thereof, and in substantially co-axial relationship therewith, is a cylindrical housing member 22 which is shown partially cut away at 23, so as to show the internal arrangement thereof. This member acts as the main support means for the elongated beam section of the apparatus. At the lower extremity of the housing 22 a radial and thrust ball bearing assembly is provided comprising the ball cup 25 fitted into the cylindrical housing 22 and the cone 26 which is held in fixed relationship with the portion 19 of the shaft 15. These two members are brought into co-operative relationship with each other by means of ball bearings 27. It will be obvious from the particular shape of the elements 25 and 26 forming this bearing that both a lateral and a thrust support is obtained.

Connected to the lower extremity of the cylindrical member 22, and shown partially broken away at its point of joining is a rod or beam member 28 whose function will be explained more fully hereinafter. At the upper extremity of the cylindrical member 22 there is positioned a pulley 30 around which is wound a cable 31. A thrust plate 32 is fastened to the pulley 30, and is adapted to rest upon ball bearings 34, the ball bearings being positioned in a thrust plate 36. Thrust plate 36 is mounted on top of the cylindrical member 22. Also fastened to the upper section of the cylindrical member 22 is a rod or beam member 38 which is shown partially in section where it joins the cylindrical member. The rod 28 is similarly shown.

An inner ring bearing 40 is mounted on the shaft 15 and has a ball race for ball bearings 42 which are housed by an outer ring bearing 44. The ball bearing assembly 40, 42, 44 enables the cylindrical housing 22 to turn freely on the stationary shaft 15.

Positioned near the lower extremity of the cylindrical member 22 is a pulley 45. The face of this pulley is arranged to receive a drive cable 48 which is shown as having been looped completely around the pulley twice. Also joined to pulley 45 is a thrust plate 49 which is recessed to provide a ball race for ball bearings 49 therein. Immediately above thrust plate 49 is a similar thrust plate 50 which is joined to a pulley 51, which pulley has wound thereabout a cable 52. For the sake of simplicity, only fragmentary stretches of the cable are shown. It will be seen,

therefore, that the pulley member 51 can rotate freely about the cylindrical member 22 on the bearing formed between the elements 48, 49 and 50. The cable 46 has one portion thereof passing over idler pulley 54 and another portion thereof passing over idler pulley 55, and thence to a drum type of drive which is shown more clearly in Fig. 3. Similarly, cable 52 passes on one portion thereof over idler pulley 56 and another portion thereof passes over idler pulley 57 to a similar remote drive.

The support members 28 and 38 have been shown as broken away, and the right hand extremities thereof are indicated at a more central fragmentary portion of Fig. 1. A shaft 62 passes through holes in the members 28 and 38, which shaft has an abutment 63 at the upper end thereof, and another abutment 64 at the lower end thereof. Positioned about and co-axial with shaft 62 is a cylindrical member 65 having fastened at the upper end thereof a beam member 66, and at the lower extremity thereof a beam member 67. Joined to the outer face of the cylindrical member 65 is a pulley or windlass 68, and the cable 53 is wound about this pulley with preferably a double turn.

Similarly to the radial and thrust bearing assembly positioned at the bottom of shaft 15 is such an assembly formed by the cone 70, the balls 71 and the cup bearing 72. Near the top of the cylindrical member 65 and on the inner section thereof the member 65 is spaced apart from, and is maintained freely rotatable about the member 62 by means of ring bearings 74 and 75 fastened one to cylindrical member 65, and the other to shaft member 62. Appropriate ball bearings 75 are positioned between the elements 74 and 76.

The beam members 66 and 67 continue as shown in the fragmentary portion further to the right of Fig. 1, these members being joined at their extremities by a vertical cross-bar 82. Cross-bar 82 supports a ball bearing assembly 83 which constitutes the fulcrum of a bell crank unit having arms 84 and 85. The microphone 86 is pivotally supported at the extremity of the member 85.

Fastened to the upper end of shaft 62 is a swivel eye arrangement 92 through the eye of which passes the cable 31. This cable is fastened to the upper extremity of the arm 84, and it will be seen that a retraction of this cable will turn the bell crank about its fulcrum thus raising the arm 85 and the microphone 86. A release of force on the cable 31 will result in the microphone 86 dropping in position due to the effect of gravity. The cable 31 passes to the left of the swivel eye 92 around pulley 30 and thence over an idler pulley 93 which is supported by the member 91. A counter-weight (not shown) may be fastened to the end of the cable so as to substantially balance the weight of the microphone.

Referring to Fig. 2, there is shown the arrangement of Fig. 1 in somewhat less detail. In this figure similar parts are referred to by the same numerals as in Fig. 1, and in addition a fair lead arrangement around the pulleys is shown. Positioned around the pulleys 45 and 51 is a cup arrangement 125 which is fastened into place, and through which are adapted to pass the cable members going to the pulleys 45 and 51. With this arrangement it is not necessary that the cable be wound about the pulleys in order to pass entirely through the member to engage the pulley 68. The openings in this arrangement are identified as 126, 127 and 128, respectively. Also,

for purposes of guiding the cable 31 there has been provided a fixed cup arrangement 129 having openings 130 and 131 therein. Similarly, embracing the pulley 68 is a cup arrangement 132 having the opening 133 therein. Specific forms of these fair lead cup arrangements have been illustrated in my co-pending application Serial No. 270,725 filed April 29, 1939, which has now matured into Patent No. 2,221,079, issued November 12, 1940.

The action of the device is as follows:

The pulling of one of the sections of cable 46 relative to the other will cause the cable to turn the pulley 45. In view of the fact that beam members 23 and 38 are fastened to the cylinder 22, and that pulley 45 also is fastened to the cylinder 22, the beam members will be turned about the axis of the pulley to a degree determined by the amount of cable wound and unwound therefrom. The degree to which this pulley turns will be dependent upon the amount of cable which is wound and unwound therefrom, and the direction in which it is turned will depend upon which way the cable winds or unwinds as the case may be. Similarly, when one section of cable 52 is moved or retracted the retracting section will pull the pulley 51 which is freely rotatable about the cylinder 22, and in turn the rotation of this pulley and the winding and unwinding of cable therefrom will cause a winding and unwinding of the same cable which passes around the pulley 68. Since the pulley 68 is fastened to the cylinder member 65, and further, since this cylindrical member is freely rotatable about the axis of the member 62, beams 66 and 67 will be turned in view of the fact that they are fastened to the cylindrical member 65, the latter in turn being fastened to the pulley 68. This means, then, that the microphone may be placed over any point in the entire area covered by 360° rotation of the pulley 45. Since it may be desired to either raise or lower the microphone as well as to place it over a definite point, the cable 31 may be retracted or let out as may be desired in order to either raise or lower the microphone, respectively.

Referring to Fig. 3, there is shown an arrangement by means of which a desired pulley or pulleys may be turned. For purposes of illustration the cable 52 has been selected. One end, 100, of this cable may be fastened to a drum member 101, and wound thereabout and thence across pulley 57 around pulley 51, and thence around pulley 68, and then returned around pulley 51 across idler pulley 56 to the drum 101, where the other end may be fastened. The drum 101 is driven through shaft means 102 which may be appropriately related thereto, either directly or through means of gears, the latter being driven by a motor. It will be appreciated that the energizing leads to the motor may be led some considerable distance away to a switch member, and by means of the switch member the motor may be controlled remotely. Again, the motor itself need not be immediately adjacent the apparatus unless it be considered that the length of the cables will be prohibitive otherwise. It will be seen that when the motor is energized a section of the cable will be unwound from the member 101, whereas another section will be wound or retracted thereupon. This will cause movement of the pulley 51, and in turn cause movement

of the pulley 68 due to the cable being wound and unwound upon the pulley 51. This illustrates the control of the section of the device from the cylinder 65 to the microphone, illustrated here as being comprised of beam members 66 and 67. A similar arrangement may be used to drive the pulley 45.

It will be appreciated that there may be departures from the exact showing illustrated in these drawings as, for instance, in actual practice it is quite likely that truss members may be fastened between the beam members so as to strengthen the device. Accordingly, I claim all structure which may fall fairly within the spirit and scope of this invention as defined in the hereinafter appended claims.

What I claim is:

1. A support apparatus including a first arm member rotatable about a fixed axis, a second arm member pivotally supported by said first member on an axis parallel to the first said axis, and separate cable-and-pulley means for independently rotating each one of said members about its axis of rotation.

2. A microphone boom including a first arm member rotatable about a fixed axis, a second arm member pivotally supported by said first member and adapted to be rotated about said pivot, separate cable-and-pulley means for independently rotating each one of said members about its axis of rotation, a third arm member pivotally supported by said second member, means for supporting a microphone on the outer end of said third member, a counter-weight, and cable means interconnecting said counter-weight and said microphone for sustaining the latter at a desired elevation.

3. Apparatus in accordance with claim 2, wherein at least one of said cable-and-pulley means includes at least one pulley member having its axis substantially coincident with the axis of said first arm member.

4. Apparatus according to claim 1 and including a third arm member pivotally supported by said second arm member on an axis which gives freedom of rotation of said third arm member in the plane of the pivotal axis of said second arm member, a useful load supported at the outer end of said third arm member, and cable-and-pulley means for rotating said third arm member on its axis.

5. Apparatus according to claim 1 in which said cable-and-pulley means includes a driven pulley mounted coaxially with respect to the pivotal axis of the second said arm member and operable to rotate the same.

6. A microphone boom comprising a support shaft, said support shaft having means for attaching said boom to the interior of a studio, a first cylindrical member arranged to rotate around said support shaft, an arm secured to said cylinder, a cable drum secured to said cylinder, a second shaft secured to said arm at the end opposite said support shaft, a second cylindrical member surrounding said second shaft, a second arm secured to said second cylinder, a third arm pivoted at right angles to the axis of said first and second support shafts, and separate means for independently moving each one of said arms.

WILLIAM C. EDDY.
